(57) **CLAIM**

The ornamental design for an eyeglass case, as shown and described.

DESCRIPTION

FIG. 1 is a top perspective view of an eyeglass case showing our new design in a closed configuration;

FIG. 2 is a front view thereof;

FIG. 3 is a back view thereof;

FIG. 4 is a left view thereof;

FIG. 5 is a right view thereof;

FIG. 6 is a top plan view thereof;

FIG. 7 is a bottom plan view thereof;

FIG. 8 is a top perspective view of the eyeglass case of FIG. 1 in an open configuration;

FIG. 9 is a bottom perspective view thereof;

FIG. 10 is a top plan view thereof;

FIG. 11 is a left-side view thereof;

FIG. 12 is a right-side view thereof;

FIG. 13 is a top perspective view of the bottom portion of the eyeglass case of FIGS. 1 through 12 shown in an alternate configuration with the detachable top removed;

FIG. 14 is a front view thereof;

FIG. 15 is a back view thereof;

FIG. 16 is a left-side view thereof;

FIG. 17 is a right-side view thereof;

FIG. 18 is a top plan view thereof; and,

FIG. 19 is a bottom plan view thereof.

Broken lines and dash-dot lines are for illustrative purposes only and show portions of the eyeglass case that form no part of the claimed design.

1 Claim, 12 Drawing Sheets
